(57) **CLAIM**

The ornamental design for a ruck strap as shown and described.

DESCRIPTION

FIG. 1 is front view of the ruck strap;

FIG. 2 is a rear view thereof;

FIG. 3 is a view of the ruck strap in an environment of use; and,

FIG. 4 is another view of the ruck strap in an environment of use.

The broken lines in the drawings illustrate environmental subject matter only and form no part of the claimed design.

1 Claim, 4 Drawing Sheets
